UNITED STATES PATENT OFFICE.

CLARENCE L. TAYLOR, OF ALLIANCE, OHIO, ASSIGNOR TO THE MORGAN ENGINEERING COMPANY, OF ALLIANCE, OHIO.

OVERHEAD TRAVELING CRANE.

No. 841,737.

Specification of Letters Patent.

Patented Jan. 22, 1907.

Application filed May 3, 1906. Serial No. 315,027.

To all whom it may concern:

Be it known that I, CLARENCE L. TAYLOR, of Alliance, in the county of Stark and State of Ohio, have invented certain new and useful Improvements in Overhead Traveling Cranes; and I do hereby declare the following to be a full, clear, and exact description of the invention, such as will enable others skilled in the art to which it appertains to make and use the same.

My invention relates to an improvement in overhead traveling cranes, and is designed more particularly as an improvement on the double-bridge crane disclosed in an application for Letters Patent executed by William H. Morgan March 16, 1906.

The Morgan application discloses a main traveling bridge carrying a main hoist-trolley and an auxiliary movable or fixed bridge carried by the main bridge and located in a plane above the main trolley.

My invention consists of a main bridge composed of two end carriages and connecting-girders carrying four parallel trackways, a main hoist-trolley mounted to travel on the inner trackways, and a gauntlet-crane mounted to travel on the outer trackway.

My invention further consists in the parts and combinations of parts, as will be more fully explained, and pointed out in the claims.

In the accompanying drawings, Figure 1 is an end view of my improvement looking toward one end of the main bridge; and Fig. 2 is a view in side elevation of the bridge, 35 showing the gauntlet-crane in end elevation.

The traveling bridge comprising two end carriages 1, mounted on wheeled trucks 2 and carrying the main girders 3, having track-rails 4, on which the main trolley 5 travels. This traveling bridge travels on the elevated trackway 6, and its trolley 5 is provided with one or more hoisting-drums 7, the chain or chains from which pass down between the main girders 3 and constitute the main hoisting-chains of the crane. The bridge thus constructed is provided with a motor and suitable gearing for propelling it, and the trolley 5 is also provided with hoist and travel motors. (Not shown.)

Secured to the end carriages near the ends of the latter are the girders 17, which latter are parallel with the main girders 3. These girders 17 are provided on their upper sur-

faces with the rails 8, on which the gauntlet-crane is mounted to travel. This crane comprises two end frames 10, each mounted on wheels 11, which travel on the rails 8 on the outer girders 17 of the main bridge, and the parallel top girders 12, secured to and connecting the end frames 10. The end frames 10 and top girders 12 are rigidly connected and securely braced, and the crane thus constructed designed to travel lengthwise the bridge-girders 17, a suitable motor and gearing being provided, if desired, for propelling this gauntlet-crane.

The top girders 12 carry rails 13, on which the wheels 14 of the trolley 15 travels. This trolley 15 is provided with a motor and gearing for actuating the hoist drum or drums thereof, and also, if desired, with a motor and gearing for propelling the trolley, and it carries a hoist-chain 16, which may be used for tilting ladles carried by the main hoist-chains, for assisting the main hoist-chains, 75 for handling light objects, and also for handling parts of the main trolley or bridge in assembling or while repairing the main crane. With this construction it will be seen that the top girders 12 extend at right angles to the 80 length of the main bridge, thus permitting the trolley 15 to move to positions to bring its hoist-chain between the main girders 3 or between the latter and the outside girders 17, while the gauntlet-crane as a whole travels 85 lengthwise the bridge, thus permitting the hoist-chain 16 to be raised and lowered past either end of the trolley.

It is evident that many slight changes might be resorted to in the relative arrangement of parts shown and described without departing from the spirit and scope of my invention. Hence I would have it understood that I do not wish to confine myself to the exact construction herein shown and described; 95

Having fully described my invention, what I claim as new, and desire to secure by Letters Patent, is—

1. The combination with a main crane having a traveling trolley therein, of a gauntlet-crane mounted to travel on the main crane parallel with the travel of the main-crane trolley. 100
2. The combination with a main crane having four parallel rails therein, of a trolley 105

mounted to travel on the two inner rails and a gauntlet-crane mounted to travel on the two outer rails.

3. The combination with a main crane having four parallel girders, of a trolley mounted to travel on the two inner girders and a gauntlet-crane mounted to travel on the two outer girders.

4. The combination with a traveling bridge having two inner rails and two outer rails, of a main trolley mounted to travel on the two inner rails, a gauntlet-crane mounted to travel on the two outer rails and a trolley mounted to travel on a trackway on the gauntlet-crane, the travel of the trolley on the latter crane being at right angles to the direction of travel of the main trolley.

5. The combination with a traveling bridge having four parallel rails, of a crane mounted to travel on the two outer rails, a main trolley traveling on the two inner rails and an auxiliary trolley mounted on the crane carried by the outer tracks and adapted to travel in a plane at right angles to the trolley on the inner rails, the said auxiliary trolley being in a plane above the main trolley.

In testimony whereof I have signed this specification in the presence of two subscribing witnesses.

CLARENCE L. TAYLOR.
